(57) CLAIM

The ornamental design for an excavator, as shown and described.

DESCRIPTION

The file of this patent contains at least one drawing executed in color. Copies of this patent with color drawings will be provided by the United States Patent and Trademark office upon request and payment of the necessary fee.

FIG. 1 is a front, top and right side perspective view of an excavator according to the design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a rear elevational view thereof.

1 Claim, 5 Drawing Sheets
